UNITED STATES PATENT OFFICE

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK

MACHINE FOR SIZING AND PERFORATING RIMS

Application filed July 8, 1926. Serial No. 121,253.

The invention relates to machines for sizing and perforating rims and particularly demountable tire carrying rims of the transversely split type. One of the objects of the invention is to provide an improved machine in which the perforating means is movable in the same direction as the sizing means. Another object is to provide dies for cooperating with the perforating means, these dies being yieldably forced in the opposite direction into engagement with the rim whereby the machine may operate upon rims having different thickness without damaging its parts. Further objects of the invention are to provide a machine in which both the sizing means and perforating means are positively actuated both toward and away from the rim and to provide single cams for actuating a sizing block and a slide carrying a perforating 20 punch.

With these as well as other objects in view, the invention resides in the novel features of construction and combinations and arrangements of parts as more fully hereinafter set forth.

In the drawings:

Figure 1 is a plan view, partly broken away, of a machine embodying my invention;

Figures 2, 3, 4, and 5 are cross sections, respectively, on the lines 2-2, 3-3, 4-4 and 5-5 of Figure 1.

The machine embodying my invention is designed to first size the transversely split demountable tire carrying rim 1 and to subsequently perforate this rim forming holes therein for receiving the valve stem of the pneumatic tire, for receiving the rivets of clamping lugs and for receiving the rivets of cooperating interlocking plates at the ends of the rim.

As shown, 2 is the bolster which may be mounted upon the bed of a press and 3 is the holder which may be secured to the rim of the press, this holder being reciprocable toward and away from the bolster. 4 are radially movable sizing blocks mounted upon the bolster 2 and guided by the gibs 5. These blocks are provided at their inner ends with the lateral projections 6 for supporting the rim 1, which is inserted in the machine with

its inner edge lowermost. One of the blocks is also preferably provided at its inner end with the flat finger 7, which is adapted to engage between the ends of the rim to position the same in the machine. These blocks are movable radially inward into engagement with the outer face of the rim to shrink this rim to size as well as to shape the rim. For moving the blocks there are the cams 8 which are secured to and depend from the holder 3, there being one cam for each block. Each cam has the cam face 9 which is engageable with the roll 10 carried upon the outer end of a block and the face 11 engageable with the roll 12, which is spaced radially outward from the roll 10 and is carried by the abutment member 13 mounted upon and secured to the bolster 2. For positively moving the blocks radially outward and away from the rim, the cams 8 are provided at their opposite sides with the cam faces 14 which are engageable with the pins 15 in axial alignment with each other and secured to the bifurcations 16 at the outer ends of the blocks.

For perforating the rim 1 to form the hole for receiving the valve stem of the pneumatic tire, I have provided the slide 17 upon one of the blocks 4, this slide being movable radially inward toward the rim and carrying the punch 18 which is engageable with the rim to perforate the same. The slide 17 is moved both toward and away from the rim positively by means of the cam 19 which is secured to and depends from the holder 3 and has the cam face 20 engageable with the outer end of the slide to move the latter radially inward and the cam faces 21 at its opposite sides engageable with the pins 22 upon the bifurcations 23 at the outer end of the slide for moving the slide radially outward. The cam 19 is so arranged relative to the cams 8 that the blocks 4 are moved radially inward to their predetermined sizing positions prior to the time the cam 19 forces the punch 18 through the base of the rim. 24 is a die for cooperating with the punch 18, this die being carried upon the radially movable slide 25 which is mounted upon the supporting block 26 and guided by suitable gibs secured to this block. This block rests upon and is secured

to the bolster 2. The slide 25 is movable radially outward to carry the die 24 into engagement with the inner face of the rim and this slide is forced radially outward by means of the cam 28 which is vertically slidably mounted upon the central block 29. This block is located centrally of the holder 3 and secured thereto and the cam 28 is yieldably forced downwardly and away from the holder by means of the coil spring 30 having its upper end abutting the holder and its lower end abutting the cam. For moving the slide 25 radially inward to disengage the die 24 from the rim, I have provided the coil spring 31 which is located in the recess 32 in the supporting block 26 and has its outer end engaging an end of this recess and its inner end engaging the pin 33 secured to the slide 25. With this arrangement, the die 24 is yieldably forced against the inner face of the rim to cooperate with the punch 18 and consequently this die does not interfere with the operation of the sizing blocks 4 in shrinking the rim.

For perforating the base of the rim near its ends to form holes for receiving the rivets which secure the cooperating interlocking plates to the rim ends, I have provided the pairs of vertically aligned punches 34 on opposite sides of this plate. These punches are carried by the radially movable slide 35 which is mounted upon a sizing block 4. For moving this slide radially inward to bring the punches into engagement with the rim to perforate the same, there is the cam 36 which is secured to and depends from the holder 3 and has the cam face 37 engageable with the outer end of the slide 35 and arranged so that the punches are brought into engagement with the rim after the sizing blocks have been moved to their predetermined sizing position. For moving the slide 35 radially outward to disengage the punches carried thereby from the rim, the cam 36 is provided at its opposite sides with the cam faces 38 which are engageable with the axially aligned pins 39 upon the bifurcations 40 at the rear end of the slide 35. For backing up the rim during the operation of the punches 34, I have provided the die 41 which is carried by the radially movable slide 42 upon the supporting block 26. This slide is yieldably moved radially outward to bring the die into engagement with the inner face of the rim by means of the cam 43 which is vertically slidably mounted upon the central block 29 upon the holder, the cam being yieldably forced downwardly and away from the holder by means of the coil spring 44 and the arrangement being such that the die 41 may cooperate with the punches 34 without interfering with the operation of the sizing blocks 4. The slide 42 is yieldably forced radially inward by means of the coil spring 45 which is located within the recess 46 in the block 26.

For perforating the rim to form holes therein for receiving the rivets of the clamping lugs which are to be permanently attached to the rim, I have provided slides 47 which are radially movable and mounted upon certain of the sizing blocks 4, the upper faces of these blocks being inclined inwardly and upwardly toward the center of the rim so that the punches 48 which are carried by these slides 47 are movable at an angle to the base of the rim. For moving these slides 47 radially inward, I depend upon the cams 8 which move the sizing blocks 4 supporting these slides. These cams, as shown, are adapted to extend through the openings 49 in the slides 47 and have the additional cam faces 50 which are engageable with the inner end walls of the openings to force the same radially inward after the sizing blocks have been forced radially inward to their predetermined sizing position. For returning the slides 47 to their original positions and disengaging the punches 48 from the rim, the cams 8 are provided with the cam faces 51 which are engageable with the rolls 52 mounted in the slides 47 at the outer ends of the openings. For backing up the rim I have provided the dies 53 which are carried by the radially movable slides 54. These slides are mounted upon the supporting block 26, the upper face of which has inclined bearing portions for engagement with the slides so that the latter move parallel to the slides 47. The slides 54 are forced radially outward to bring their dies 53 into contact with the rim by means of the cams 55 which are vertically slidably mounted upon the central block 29. The cams 55 are forced downwardly and away from the holder 3 by means of the coil springs 56 so that the dies may back up the rim without interfering with the operation of the sizing blocks 4. For moving the slides 54 radially inward to disengage their dies from the rim, there are the coil springs 57 which are located in the recesses 58 formed in the upper face of the supporting block 26.

From the above description it will be readily seen that I have provided an improved machine for sizing and perforating a rim in which the sizing blocks and punches are both movable in the same direction into engagement with the rim and in which the dies for cooperating with the punches and backing up the rim are movable in the opposite direction and operate without interfering with the operation of the sizing blocks. It will also be seen that I have provided means for positively moving both the sizing blocks and slides carrying the punches in opposite directions and that the slides for carrying certain of the punches are actuated by the cams for moving certain of the sizing blocks.

What I claim as my invention is:

1. In a machine for sizing and perforating a rim, the combination with means movable

into engagement with the rim to size the same, of means movable subsequently in a corresponding direction and independent of the sizing means into engagement with the rim to perforate the same and means cooperating with said perforating means and movable in the opposite direction into engagement with the rim.

2. In a machine for sizing and perforating a rim, the combination with blocks movable toward the center of the rim into engagement with the rim for sizing the same, of punches subsequently movable toward the center of the rim into engagement with the rim for perforating the same and dies cooperating with said punches and movable away from the center of the rim into engagement therewith.

3. In a machine for sizing and perforating a rim, the combination with blocks movable radially into engagement with the rim for sizing the same, of punches subsequently movable in a corresponding direction into engagement with the rim for perforating the same, and means for moving said blocks and punches in timed relation including a single cam for actuating a block and a punch.

4. In a machine for sizing and perforating a transversely split rim, the combination with blocks movable into engagement with the rim to size the same, of punches subsequently movable in the same direction into engagement with the rim to perforate the same and means including transversely movable cams for actuating said blocks and punches positively both toward and away from the rim.

5. In a machine for sizing and perforating a rim, the combination with blocks movable radially inward into engagement with the rim for sizing the same, punches movable radially inward into engagement with the rim for perforating the same, dies for cooperating with said punches movable radially outward into engagement with the rim, and means for yieldably moving said dies.

6. In a machine for sizing and perforating a rim, the combination with blocks movable radially inward into engagement with the rim for sizing the same, of slides mounted upon said blocks, punches carried by said slides for engagement with the rim to perforate the same, and means for actuating each of said slides and the block upon which said slide is mounted including a single cam having portions for successively actuating said block and slide.

7. In a machine for sizing and perforating a rim, the combination with blocks movable radially inward into engagement with the rim for sizing the same, of slides mounted upon said blocks, punches carried by said slides engageable with the rim to perforate the same, dies movable radially outward into engagement with the rim for cooperating with said punches, slides carrying said dies, a holder movable transversely of the direc-

tion of movement of said blocks and slides, cams upon said holder for actuating said blocks and first-mentioned slides, cams carried by said holder and yieldable means between said cams and holder for moving the former from the latter into engagement with 70 said last-mentioned slides.

8. In a machine for sizing and perforating a rim, the combination with means movable toward the center of the rim into engagement therewith for sizing the same, of means movable independently of and in a corresponding direction to the said sizing means into engagement with the rim to perforate the same, and means cooperating with said perforating means and movable in the opposite direction into engagement with the rim.

9. In a machine for sizing and perforating a rim, the combination with means movable into engagement with the rim to size the same, of means subsequently movable relative to said sizing means and in a corresponding direction into engagement with the rim to perforate the same and means cooperating with said perforating means and movable in 90 the opposite direction into engagement with the rim.

In testimony whereof I affix my signature.
WILLIAM N. BOOTH.
